UNITED STATES PATENT OFFICE.

EDWARD S. DE TAMBLE, OF INDIANAPOLIS, INDIANA, ASSIGNOR TO THE UNION EMBOSSED MACHINE COMPANY, OF SAME PLACE.

EMBOSSING-MACHINE.

SPECIFICATION forming part of Letters Patent No. 572,197, dated December 1, 1896.

Application filed July 17, 1896. Serial No. 599,509. (No model.)

To all whom it may concern:

Be it known that I, EDWARD S. DE TAMBLE, a citizen of the United States, residing at Indianapolis, in the county of Marion and State of Indiana, have invented certain new and useful Improvements in Embossing-Machines, of which the following is a specification.

The object of my said invention is to provide a means whereby an embossing-machine may be employed to ornament curved or circular wooden structures, such as bicycle-wheel rims, mud-guards, &c.

An embossing-machine provided with attachments embodying my said invention will be first fully described and the novel features thereof then pointed out in the claims.

Referring to the accompanying drawings, which are made a part hereof and on which similar letters of reference indicate similar parts, Figure 1 is a perspective view of such an embossing-machine; Fig. 2, a central vertical sectional view of the upper end thereof, and Fig. 3 a detail sectional view on the dotted line 3 3 in Fig. 2.

In said drawings the portions marked A represent the frame of the machine; B, the main roll-carrying shaft; C, the embossing-roll or die-spindle; D, the burner therein, and E a guide-supporting shaft or rod.

The frame A is a strong, heavy frame suitably arranged to carry the mechanism, and is preferably mainly in the form of heavy castings, as shown.

The shaft B is mounted in bearings in the heavy vertically-adjustable frame B', which is mounted in ways in the sides of the frame A, and at the upper end extends out into substantially the form of a table, but with an open upper side. This vertically-adjustable frame or table is adapted to be raised and lowered quickly to and from certain determinate positions by a rock-shaft 1, having cams 2 and operated by a hand-lever 3. Said

cams 2 operate against the blocks 4, which are connected to the rods 5, the upper ends whereof are seated in sockets in the frame B'. These rods 5 are screw-threaded and enter screw-threaded perforations in the blocks 4.

They are provided with bevel-pinions 6, which engage with corresponding pinions 7 on the

shaft 8. By this means these rods 5 may be simultaneously revolved and thus the distance between the blocks 4 and the frame B' adjusted. I have shown a sprocket-wheel 9, 55 having a sprocket-chain 10, (running to a suitable hand-operated shaft, not shown,) as a means for revolving this shaft; but obviously the sprocket-wheel 9 might be a plain hand-wheel and the shaft 8 thus operated directly by 60 hand or any other suitable means for the purpose employed. Said shaft B bears the various disks b, b', and b², which serve to support the wooden pieces being embossed while the embossing operation is in progress. I 65 have shown three of the disks b, three of the disks b', and one disk b²; but obviously any desired number may be employed. These disks are shown as separated by washers and held in place on the shaft B by suitable collars. 70

The spindle C is hollow and carries the embossing disks or dies c, c', and c², which correspond to the companion disks b, b', and b² and which are engraved on their peripheral 75 surfaces with the figures desired to be embossed on the wood. Said disks are separated by washers and secured upon the spindle in the same manner that the corresponding disks are separated and secured upon the shaft B. 80 This spindle is supported by heavy roller-bearings at each end and comes directly in contact with the rollers C', forming the operative part of said bearings. 85

The burner D is a tubular burner and extends within the opening in the spindle C. Securely attached to the outer end of this burner is the cap D', which rests immediately within the extreme outer end of the spindle C and is adapted to support the burner, although it is not fastened to said spindle, and is consequently capable of remaining in its position while the spindle revolves. Said cap D' has a number of fine perforations surrounding the opening, by which the burner D is 90 coupled thereto for the admission of air, and the spindle C is provided with perforations at the other end of the burner, as shown in Fig. 2, for the escape of the products of combustion. A neck or elbow D² is connected to the cap D', and to this in turn is connected a flexible tube or hose D³, which leads to a 95 100

"mixer" D⁴, to which the gas-pipe D⁵ leads, whereby the fuel-gas, which I prefer to use with this machine, is supplied thereto.

The shaft or rod E is mounted in bearings 5 e on standards E' on the frame A. These standards are slotted and the bearings are thus rendered adjustable, as plainly shown, so as to accommodate the guides to work of different size. Upon the outer end of this 10 shaft or rod are the guide-rollers E², which engage with and support the bicycle-rims while being embossed.

In the machine as illustrated the provision is made for the embossing of three wheel-guards X, three wheel-rims Y, and one chain-guard Z. The wheel-guards X, being in the form of strips, although somewhat curved, may pass within the machine between the bearings in the frame which carry the rolls 15 and dies. The rims Y being annular in form, it is necessary that the rolls and dies by which they are treated should be outside the bearing in order that they may be removed and replaced. It is also desirable that the 20 chain-guard be similarly outside of the bearing, for, while not completely connected together at the ends, it is of such form as to render its introduction inside of the bearings very difficult. As the rims Y extend a considerable distance above the point where they 25 are operated upon, it is necessary that their upper and otherwise free portions should be accurately supported in position in order that the work may be uniform, and the shaft E, 30 with its guide-rolls E², is provided accordingly, said guide-rolls being held between collars e², as shown, which prevent them from moving endwise of the shaft by which they are carried, although left free to revolve 35 thereon.

In order that the rims Y may be removed and replaced readily without uncoupling the fuel hose or tube D³, said tube is bent around and conducted back, substantially parallel 40 with the spindle C, to a point outside of the rolls and dies by which the rims are treated.

By the machine shown I find that I am enabled to satisfactorily emboss these thin wooden parts, which have not heretofore been 45 capable of being successfully provided with

ornamentation of this character. Manifestly, from the nature of the structures to be so operated upon, the embossing must not be deep, and consequently the spindle and shaft may extend outside the bearings by which they are 55 supported and still have sufficient strength and rigidity to perform the work.

Having thus fully described my said invention, what I claim as new, and desire to secure by Letters Patent, is—

1. The combination, in an embossing-machine, of a main framework, an adjustable frame or table, a main shaft carried thereby and having an end which projects to the outside of the framework of the machine, and is 60 there provided with supporting disks or rollers for the work to be treated, a spindle mounted in bearings in the main framework and also extending to outside the frame of the machine and there provided with embossing 65 rolls or dies, a burner within said spindle, a cap loosely mounted in the end of said spindle and adapted to remain stationary while the latter revolves for carrying the burner at its outer end, a flexible coupling connected to 70 said cap and extending back substantially parallel with the spindle to alongside the frame and thence to the gas-fuel-supply pipe, and said pipe, whereby wheel-rims and similar annular structures may be embossed upon 75 their interior sides, substantially as shown and described.

2. An embossing-machine, the spindle whereof extends to outside the framework thereof and carries embossing rolls or dies 80 thereon, and a heat-supplying tube connected to the burner-cap in the outer end of the spindle and extending thence back alongside the spindle to near the framework, thus enabling 85 annular structures to be placed over the spindle and operated upon, substantially as and for the purposes set forth.

In witness whereof I have hereunto set my hand and seal, at Indianapolis, Indiana, this 13th day of July, A. D. 1896.

EDWARD S. DE TAMBLE. [L. S.]
